Buell Moore, Houston, Tex., assignor to Esquire, Inc.,
New York, N.Y., a corporation of Delaware

Filed Jan. 8, 1963, Ser. No. 73,086

Term of patent 14 years

(Cl. D48—23)

FIG. 1 is a perspective view as seen from the corner and bottom of a suspended combination transformer and light fixture;

FIG. 2 is an enlarged side elevation thereof;

FIG. 3 is a top plan view thereof; and

FIG. 4 is a bottom plan view thereof.

The dots on the side of the light fixture indicate a roughened surface.

I claim:

The ornamental design for a suspended combination transformer and light fixture, substantially as shown and described.
